2 SHEETS—SHEET 2.

UNITED STATES PATENT OFFICE.

RICHARD H. WELLES, OF KENOSHA, WISCONSIN, ASSIGNOR TO THE RADGER BRASS MFG. CO., OF KENOSHA, WISCONSIN, A CORPORATION OF WISCONSIN.

LAMP.

981,046.

Specification of Letters Patent. Patented Jan. 10, 1911.

Application filed March 21, 1910. Serial No. 550,708.

To all whom it may concern:

Be it known that I, RICHARD H. WELLES, a citizen of the United States, residing in the city of Kenosha, county of Kenosha, and State of Wisconsin, have invented certain new and useful Improvements in Lamps, of which the following is a specification.

This invention relates to improvements in lamps and refers more particularly to substitute burners for lamps of that type used in automobiles, motor cars, and the like.

Among the salient objects of the invention are to provide a construction in which different kinds of illumination, such as gas and electric light, may be used in one and the same lamp; to provide a construction of the above character in which the two kinds of burners are mounted upon a common rock shaft and alternately shifted into and out of focus by means of a simple thumb lever; to provide simple and improved means for automatically locking the burners in either of their positions; to provide a construction which is extremely reliable in operation, devoid of delicate or relatively weak parts, and which at the same time can be economically manufactured; and in general to provide an improved construction of the character referred to.

The invention consists in the matters hereinafter described and more particularly pointed out in the appended claims.

In the drawings—Figure 1 is a side elevation of a motor car lamp equipped with my invention, part of the lamp being broken away and shown in section, in order to more clearly bring out details of construction; Fig. 2 is a fragmentary transverse sectional view taken on lines 2—2 of Fig. 1 and looking in the direction of the arrows; Fig. 3 is a fragmentary sectional view generally similar to Fig. 3 but showing the burners in the opposite position from that shown in Fig. 2; Fig. 4 is an enlarged detail sectional view taken on lines 4—4 of Fig. 2 and looking in the direction of the arrows; Fig. 5 is a fragmentary inverted plan view of the lower portion of the lamp and showing more particularly the locking device. Fig. 6 is a perspective view of the base plate.

The lamp is provided with a reflector 1 at its rear end as shown at Fig. 1.

At its lower side the main body 2 of the lamp is apertured as shown at 3 and across this aperture upon the inner face of the

lamp is adjustably mounted a base or supporting plate 6. At diagonally opposite corners the plate is provided with a pair of screws 8, 8, and a confining washer 9. The lower end of each screw extends through a closed slot 10 and the plate may be adjusted to or from the rear of the lamp by loosening the confining screws 8 in an obvious manner. This supporting plate 6 is centrally apertured as shown at 7 and provided with counter recesses 7' through each of which projects a journal bearing 4' carried by the corresponding bracket 4. Each of these brackets 4 is secured to the base plate 6 by means of suitable screws 5, 5. It is to be understood, of course, that the opposed bearing eyes 4' are in alinement. Between these bearings is rotatably seated a rock shaft 11 having reduced journal extensions 12 extending into the bearing eyes 4'. 75

To the rock shaft is integrally connected a pair of burners 13 and 14 which in the present instance are adapted for use with gas and electric light respectively. Accordingly, the gas nozzle 13 communicates through the rock shaft with the usual inlet tube 15. In a similar manner the bulb stem 14 which supports the bulb 16 is provided with the insulated connecting wires 17. These burners are angularly disposed relative to each other, so that when one of the burners is swung into vertical position *i. e.* in the focus of the lamp, the other burner is swung toward the side of the lamp and as far out of the way as possible. In order to limit the movement of the burners in either direction, the base plate 6 is provided at opposite sides with a pair of upstanding ribs or stops 18 and 19 which are adapted to engage shoulders 20 and 21 formed in the respective burner stems 13 and 14. It may here be noted that the burners are so angularly disposed that when one burner engages its corresponding stop, the other burner will be in its vertical focal position. The burners are locked in either of their positions by means of a thumb lever 22 pivotally mounted between a pair of downwardly projecting ears 23 carried by the rock shaft 11. This thumb lever is provided with a pair of opposed fingers 25, 26, the frame of which is adapted to have locking engagement with a stop lug 24 formed by cutting away a portion of the lower face of the adjacent bracket 4. The finger 25 is normally forced behind 105

- this lug 24 by means of a coiled expansion spring 28, seated in a suitable socket in the base of the rock shaft and engaging the opposite finger 26. When the rock shaft is 5 swung into either of its positions by means of the thumb lever, the spring forces the finger 25 into locking engagement with the lug 24 and thus holds the burners rigidly in the desired position.
- 10 The operation of the device may be briefly described as follows: If the burners are in the position shown in Fig. 2, *i. e.*, with the gas nozzle in focal position, they will be shifted into the opposite position by first 15 moving the finger 25 out of engagement with the lug and then shifting the rock shaft. The thumb lever is then released and automatically forced into its opposite locking position by means of the spring 28.
- 20 The invention is not limited to the details of construction shown except as set forth in the appended claims.

I claim as my invention:

1. The combination with a lamp having a reflector, of a pair of angularly disposed rigidly connected burners adapted for use with different kinds of illumination, means for shifting either of said burners into and out of focal position and means for locking 25 said burners in either position.
2. The combination with a lamp body having a reflector, of a pair of burners adapted to be alternately rocked into and out of focal position, and means for locking 30 said burners in either position.
3. The combination with a lamp body, of a reflector therein, a pair of angularly disposed burners mounted therein, connected

to move in unison and adapted to be shifted into and out of focal position, and means 40 for locking said burners in either position.

4. The combination with a lamp body having a reflector, of a rock shaft journaled therein, a pair of angularly disposed burners connected to said rock shaft, and adapted 45 to be shifted into and out of focal position, and a lever for locking said rock shaft when the burners are shifted in either position.

5. The combination with a lamp body 50 having a reflector therein, of a pair of depending bracket supports, a rock shaft journaled between said brackets, a pair of angularly disposed burners carried by said rock shaft, and adapted to be shifted into and 55 out of focal position alternately and means for automatically locking said rock shaft after the burners have been shifted into either position.

6. The combination with a lamp body 60 having a reflector, of a pair of angularly disposed burners connected together and alternately movable into and out of focal position, and means for locking said burners in either position. 65

7. The combination with a lamp body having a reflector, of a pair of angularly disposed burners mounted to move in unison and adapted for use with different kinds of illumination, and shifting mechanism for alternately moving one of said burners into 70 and the other out of focal position.

RICHARD H. WELLES.
